UNITED STATES PATENT OFFICE.

CHARLES F. MITCHEL, OF ROCHESTER, NEW YORK, ASSIGNOR TO BASTIAN BROTHERS COMPANY, OF ROCHESTER, NEW YORK, A CORPORATION OF NEW YORK.

DIRECTION SIGNAL.

Application filed February 28, 1925. Serial No. 12,244.

The present invention relates to direction signals and more particularly to the type designed for attachment to the hand of the driver of an automobile for night signaling to vehicles in rear. An object of this invention is to provide a simple and inexpensive construction in which a reflector carries an attaching means for passing about a hand of the driver.

10 To these and other ends, the invention consists of certain parts and combinations of parts, all of which will be hereinafter set forth: the novel features being pointed out in the appended claim.

15 In the drawings:

Fig. 1 is a perspective view of a signaling device constructed in accordance with this invention;

20 Fig. 2 shows the device partially in section; and

Fig. 3 is a rear view of the disk.

Referring more particularly to the illustrated embodiment of the invention, 1 indicates a disk or plate which has means 25 such as a ring 2 cemented or otherwise secured thereto and overhanging the perimeter of a reflector 3. This reflector has a concave rear face coated with a reflecting material 4, such as mercury, the 30 outer face of this reflector being provided with a number of facets.

The concave face provides in rear of the reflector a space or compartment and the plate in rear of this compartment is provided with two slots 6. An elastic band 7 35 has a hem 8 or other enlargement at one end

lying in the chamber, the band passing through one of the slots, then inwardly into the chamber through the other slot and out again from the chamber through the first 40 mentioned slot on the inner side of the hem end of the band. This arrangement permits the band to be adjusted to fit different sizes of hands and the interlacing as described produces friction on the band to hold it in 45 its adjusted position.

It will thus be seen that there has been provided a hand signal for use for automobilists for signaling at night to vehicles in rear of an intention to stop or to turn. 50 The reflector tends to collect rays from the headlights of the vehicles in rear and reflect the same back to the driver of such rear vehicles. The facets of the reflector tend to add to the brilliancy of the same.

55 What I claim as my invention and desire to secure by Letters Patent is:

A signal of the class described comprising a reflector having a concave rear face, a flat disk having means thereon overhanging the 60 edges of said reflector to secure the latter to the disk so as to provide a chamber in rear of the reflector, said disk also having two slots communicating with the chamber formed in rear of the reflector, an attaching 65 band having an enlargement at one end lying in the chamber, said band extending through one of the slots to the outside of the disk, then through the other slot and out again through the first mentioned slot.

CHARLES F. MITCHEL.
